Atty's.*

UNITED STATES PATENT OFFICE.

HERBERT J. ARMSTRONG, OF ATLANTIC CITY, NEW JERSEY.

DESIGN FOR A COMBINATION MIRROR, RAZOR-STROP, AND MATCH-IGNITER.

53,282.

Specification for Design.

Patented May 13, 1919.

Application filed January 2, 1919. Serial No. 269,355. Term of patent 3½ years.

To all whom it may concern:

Be it known that I, HERBERT J. ARMSTRONG, a citizen of the United States, residing at Atlantic City, N. J., have invented a new, original, and ornamental Design for Combination Mirror, Razor-Strop, and Match-Igniter, of which the following is a specification, reference being had to the accompanying drawing, forming a part thereof.

The figure is a front view of a combination mirror, razor strop and match igniter showing my new design.

I claim:

The ornamental design for a combination mirror, razor strop, and match igniter, as shown.

HERBERT J. ARMSTRONG.
